US00D759229S

(12) **United States Design Patent**
Gibb et al.

(10) **Patent No.:** **US D759,229 S**
(45) **Date of Patent:** **** Jun. 14, 2016**

(54) **FUEL TANK FRAME ASSEMBLY**

(71) Applicants: **Gary Gibb**, Stow, OH (US); **Michael Pintz**, Fairview Park, OH (US); **Stephen Polatas**, North Canton, OH (US)

(72) Inventors: **Gary Gibb**, Stow, OH (US); **Michael Pintz**, Fairview Park, OH (US); **Stephen Polatas**, North Canton, OH (US)

(73) Assignee: **WORTHINGTON INDUSTRIES**, Columbus, OH (US)

(**) Term: **14 Years**

(21) Appl. No.: **29/520,243**

(22) Filed: **Mar. 12, 2015**

Related U.S. Application Data

(63) Continuation of application No. 29/473,251, filed on Nov. 20, 2013, now abandoned.

(57) **CLAIM**

The ornamental design for a fuel tank frame assembly, as shown and described.

DESCRIPTION

FIG. 1 is a perspective view of a fuel tank frame assembly; FIG. 2 is a back view of the fuel tank frame assembly of FIG. 1;

FIG. 3 is a front view of the fuel tank frame assembly of FIG. 1;

FIG. 4 is a first side view of the fuel tank frame assembly of FIG. 1;

FIG. 5 is a second side view of the fuel tank frame assembly of FIG. 1, wherein the second side is opposite the first side of FIG. 4;

FIG. 6 is a top view of the fuel tank frame assembly of FIG. 1; and,

FIG. 7 is a bottom view of the fuel tank frame assembly of FIG. 1.

The broken lines in the drawings depict environmental subject matter that forms no part of the claimed design.
